UNITED STATES PATENT OFFICE.

CHARLES WILFRED BIRKIN AND EDWIN THOMAS SANDS, OF BROADWAY, NOTTINGHAM, ENGLAND, ASSIGNEES TO BIRKIN AND COMPANY, OF BROADWAY, NOTTINGHAM, ENGLAND.

DESIGN FOR A LACE MAT.

Application filed April 21, 1927, Serial No. 21,667, and in Great Britain February 17, 1927. Term of patent 3½ years.

To all whom it may concern:

Be it known that we, CHARLES WILFRED BIRKIN and EDWIN THOMAS SANDS, subjects of the King of Great Britain, residing at Broadway, Nottingham, England, have invented a new, original, and ornamental Design for Lace Mats, of which the following is a specification, reference being had to the accompanying drawing, forming part thereof.

The drawing shows a lace mat embodying the design.

We claim:

The ornamental design for a lace mat substantially as shown.

CHARLES WILFRED BIRKIN.
EDWIN THOMAS SANDS.
